[57] ABSTRACT

A reciprocating type portable filing machine of a fluid actuable structure having a finger operable valve mechanism for the pressured fluid introduction, a cylindrical reciprocator which is incorporated within a main body being resiliently loaded in axial directions, a piston slideable within the reciprocator in directions opposite to the sliding directions of the latter and a filing part coactive with the reciprocator for the filing work.

RECIPROCATING TYPE PORTABLE FILING MACHINE

The present invention relates to a reciprocating type portable filing machine, more particularly relates to a portable filing machine of a reciprocating type which utilizes a combined effect of fluid actuated piston movement with resilient repulsion, the fluid being in general given in the form of compressed air.

Many proposals have been made for the improvement of the structures and functions of reciprocating type portable filing machines. Nevertheless, most of the conventional portable filing machines of this type are still indispensably accompanied by undesirable drawbacks such as considerable vibrations and shocks during the filing work which are uncomfortable and irritating to the operator of the machine, and rough movement of the reciprocating part or parts relative to the main part of the machine. For these reasons, portable filing machines of "reciprocating type" have not been as welcomed in the market as portable filing machines of "rotary type."

It is the object of the present invention to provide a reciprocating type portable machine capable of performing surface filing without irritating and uncomfortable vibrations and shocks to the hands of the operators.

It is also the object of the present invention to provide a reciprocating type portable filing machine capable of performing surface filing with assured smooth movement of reciprocating part or parts relative to the main part of the machine. In order to attain the above-described objects, the portable filing machine of the present invention includes a hollow main body, a main hand grip disposed to the top of the main body, a fluid actuatable reciprocator incorporated within the main body and resiliently loaded in axial directions, a finger operable valve mechanism incorporated in the main hand grip so as to control the flow of the actuating fluid, a piston encased within the reciprocator, a filing part coactive with the reciprocator for the surface filing work and a roller bearing assembly inserted between the main body and the filing part. Fluid exhaust passages connected to chambers on both sides of the piston within the reciprocator may desirably join together at a point appreciably remote from their upstream ends so that the discharge of the used fluid should not be influenced by the pressure prevailing within the reciprocator.

Further features and advantages of the present invention will be made clearer from the ensuing description, reference being made to an embodiment illustrated in the accompanying drawings, in which:

FIG. 1 is a vertical cross sectional plane view of an embodiment of the portable filing machine of the present invention;

FIG. 2 is a cross sectional plane view taken along a line 2-2 in FIG. 1;

FIG. 3 is a cross sectional plane view taken along a line 3-3 in FIG. 1;

FIG. 4 is a cross sectional plane view taken along a line 4-4 in FIG. 1;

FIG. 5 is a cross sectional plane view taken along a line 5-5 in FIG. 1;

FIG. 6 is a vertical cross sectional plane view of a main part of the main hand grip of the apparatus shown in FIG. 1;

FIG. 7 is an explanatory perspective plane view of the roller bearing assembly in a disassembled condition.

Referring to FIG. 1, the entire structure of a basic embodiment of the portable filing machine of the present invention is shown. As major elements, the machine includes a hollow main body 30; a main hand grip 10, secured on the main body 30, for handling of the machine by operators; a mechanism incorporated inside the main hand grip 10 for control of flow of fluid me-

diun used for actuation of the filing work; a fluid actuated cylindrical reciprocator 60 disposed axially slidably within the main body 30; an axially slidable piston 80, contained within the cylindrical reciprocator 60, and; a filing part 90, disposed downside of the main body 30 in rigid connection with the reciprocator 60. Further, in the case of the illustrated embodiment, the main hand grip 10 is accompanied by an auxiliary front hand grip 38 threaded into the front end part of the main body 30.

The main hand grip 10 is provided with a front bore 16 opening on the front side at 17. The bore 16 merges into a fluid intake passage 11 formed in the rear portion of the grip 10. At the front opening 17 of the bore 16, a trigger 19 is pivoted to the body of the grip 10 via a lateral pin 20. The trigger 19 possesses a front nose 18 for operation by an operator's thumb or fingers. The trigger 19 is accompanied with a rearwardly extending valve actuator 21 which is pivoted to the former via a lateral pin 22. The rear end of the valve actuator 21 confronts the front end of a valve member 23 incorporated within the rearward extension of the bore 16.

The fluid intake passage 11 is connected to a given supply source of the fluid medium via a fluid intake pipe 24 which is threaded at its downstream end into the passage 11. This fluid intake passage 11 is connected to a vertical fluid intake passage 12. A fluid exhaust passage 13 is formed in the rear portion of the grip 10, separately from the fluid intake passage 11, and is connected to a horizontal fluid exhaust passage 15 via a vertical fluid exhaust passage 14. The fluid exhaust passage 13 opens into a fluid exhaust pipe 25 spacedly embracing the fluid intake pipe 24. As is clear in the drawing, the fluid exhaust pipe 25 is connected air tight to the rear end of the grip 10.

The main body 30 is secured to the bottom face of the main hand grip 10 by set bolts 27 and 28 via an intermediate gasket 26. The main body 31 is internally provided with a cylinder bore 31 which extends over the entire length of the main body and provided on the outside with an auxiliary hand grip 38 threaded at its leg portion into the front portion of the main body.

In the main body 30, a fluid passage 34 is formed and connected with the 2nd fluid exhaust passage 14 running through the body of the hand grip 10. The fluid passage 34 runs horizontally, parallel to the third fluid exhaust passage 15. The fluid passage 34 terminates at a rear annular groove 35 formed in the wall of the main bore 31. Similarly, the third fluid exhaust passage 15 runs further forward through the body of the hand grip 10 and is connected to a front annular groove 37, formed in the wall of the main bore 31, via a vertical fluid passage 36 formed through the main body 30. The main body 30 is further internally provided with a vertical hole 33 which joins the main bore 31 at a right angle and is connected to the second fluid intake passage 12 in the main hand grip 10 via a connecting passage 32.

The front end of the main bore 31 is closed by an end wall 41 detachably fixed thereto by a suitable fastener ring 39. The end wall 41 is internally and coaxially accompanied with a cushion abutment 43 secured thereto by a set bolt 45. The cushion abutment 43 is made up of elastic materials such as rubber or the like. A coil compression spring 47 is inserted over the cushion abutment 43 and extends between the inner face of the end wall 41 and the front face of the fluid actuated cylindrical reciprocator 60.

On the rear end side of the main bore 31, an end wall 42, a fastener ring 40, a cushion abutment 44, a set bolt 46 and a coil compression spring 48 are arranged in a same order as on the above-described front end side of the main bore 31. Further, in the front and rear end regions, the main bore 31 is provided with longitudinal guide grooves 49 and 50, respectively, formed in its wall.

The fluid actuated cylindrical reciprocator 60 is contained within the main bore 31 in an axially slideable arrangement. Both ends of the reciprocator 60 are closed by sealing caps 71 and 72 which are fixed in position by pins 69 and 70, respectively. As already described, outer faces of the caps 71 and 72 are in pressure contact with inner ends of the compression springs 47 and 48, respectively. The sealing caps 71 and 72 are provided with downwardly protruding carrier legs 73 and 74, respectively. The carrier legs 73 and 74 serve for assemblage of the filing part 90 to the main body 30 as later explained in more detail.

Re the fluid system, the reciprocator 60 is provided with fluid inlet ports 61 and fluid outlet ports 62 and 63 formed through its peripheral wall. Further, the reciprocator 60 is provided with a rear annular groove 65 and a front annular groove 64 formed in its peripheral wall 68. The wall 68 is further provided with a cut-out 66 and a passage 67 connected to the cut-out 66, the cut-out 66 forming reservoir for the pressurized fluid. The diameters of the fluid inlet ports 61 decrease from the middle one to the terminal ones 61a and 61b. In the disposition shown in FIG. 1, the annular grooves 64 and 65 of the reciprocator 60 respectively meet the annular grooves 37 and 35 of the main body 30.

The piston 80 is encased within the reciprocator 60 in an axially slideable arrangement leaving fluid chambers 77, 78 on both ends thereof. This piston is provided with a fluid passage 81 opening on one hand into the leftward fluid chamber 77 and on the other hand into an annular groove 84 formed on its periphery; and another fluid passage 82 opening on one hand into the rightward fluid chamber 78 and on the other hand into an annular groove 83 formed on its periphery also.

The filing part 90 includes a support layer 93 secured to the carrier legs 73 and 74 of the reciprocator 60 by set bolts 75 and 76 via intermediate members 91 and 92. A body file 95 is attached to the support layer 93 by holder mechanisms 97 and 98 while sandwiching a cushion layer 94 of elastic nature and an intermediate friction layer 96 for preventing undesirable accidental slippage of the body file 95. The holder mechanisms 97 and 98 are located on both ends of the length of the filing part 90.

In between the main body 30 and the filing part 90, there is disposed a roller bearing assembly 100 which is shown in FIG. 7 in a disassembled disposition. As is clear from the drawing, the roller bearing assembly 100 includes, from top to bottom, a carrier plate 101

which carries a plurality of bearing rollers 102. The bearing rollers 102 expose their peripheries somewhat beyond both faces of the carrier plate 101 and are arranged spacedly side by side with their axles being at right angles with respect to the reciprocating direction of the filing part 90. A supporter plate 103 is placed beneath the bearing rollers 102. The above-mentioned three members 101, 102 and 103 are received within a guide frame 104 mounted on the support layer 93. 10 The inner length of the guide frame 104 is selected somewhat larger than the length of the carrier plate 101 so that the latter can slide longitudinally within the guide frame 104 upon reciprocation of the filing part 90.

15 In practical use the portable filing machine of the present invention, having the above-explained structure functions in the following manner.

In the first place, the nose 18 of the trigger 19 is turned by thumb or finger from the disposition shown 20 in FIG. 1 to that shown in FIG. 6 so that the valve member 23 is forced to slide rearwardly via the valve actuator 21. By this sliding of the valve member 23, the fluid intake passage 11 is brought into communication with the second fluid intake passage 12. Upon establishment 25 of this communication, the pressurized fluid supplied from the fluid intake pipe 24 is brought into the interior of the reciprocator 60 passing through the fluid intake passage 11, the second fluid intake passage 12, the connecting passage 32 (see FIG. 3) and the vertical hole 33 of the main body 30. Once the trigger 19 is turned 30 in this way, the trigger 19 and the valve member 23 retain the disposition shown in FIG. 6 because the lateral pin 20 of the trigger 19 assumes a position above the level of the axis of the valve actuator 21. In other words, the above-mentioned fluid flow communication 35 is maintained without accidental interruption.

Now in the disposition shown in FIG. 1, both the reciprocator 60 and the piston 80 are positioned about 40 midway in main bore 31 interior. But, in practical operation, they move in directions opposite each other.

Assuming that the piston 80 is positioned on a little 45 to the right of that shown in the drawing, the pressurized fluid is introduced into the right side fluid chamber 78 via the fluid inlet port 61 of the reciprocator 60, the annular groove 83 on the periphery of the piston 80 and the fluid passage 82 within the body of the piston 80. The increased pressure inside the fluid chamber 78 caused by this pressurized fluid introduction presses the inner face of the right side sealing cap 72 and, consequently, the reciprocator 60 as a whole is moved rightwards in the drawing, i.e. rearwards in the structure of the filing machine. In this case, the magnitude of the fluid pressure within the chamber 78 exceeds the magnitude of the force produced by the right side compression spring 48. On the other hand, this fluid pressure within the right side (rear side) fluid chamber 78 forces the piston 80 to slide leftwards (forwards) in the reciprocator 60. By this leftward sliding of the piston 80, the right side fluid outlet ports 63 come into communication with the interior or reciprocator 60, i.e. the right side fluid chamber 78, and the fluid in the chamber 78 is discharged outside the machine via the port 63, the annular groove 65 of the reciprocator 60, the annular groove 35 of the main body 30, the fluid passage 34, the exhaust passages 14 and 13 and the fluid exhaust pipe 25.

By the above-mentioned leftward movement of the piston 80, the annular groove 84 of the piston 80 is registered at the fluid inlet port 61 of the reciprocator 60 and the pressured fluid is now introduced into the leftward fluid chamber 77 via the inlet port 61, the annular groove 84 and the fluid passage 81 of the piston 80. Due to this introduction of the pressured fluid into the chamber 77, the piston 80 is now urged to move rightwards.

Separately from this, after the above-mentioned discharge of the pressured fluid out of the right side fluid chamber 78, the reciprocator 60 is forced to move leftwards by the repellent force produced by the right side compression spring 48. This leftward movement of the reciprocator 60 is further assisted by the fluid pressure within the chamber 77 already caused by the leftward sliding of the piston 80 in the reciprocator 60. The leftward movement of the reciprocator 60 associated with the rightward sliding of the piston 80 within the reciprocator 60 allows communication between the leftward fluid outlet port 62 and the interior of the reciprocator 60 and, due to the establishment of this fluid flow communication, the pressured fluid is discharged from the left side fluid chamber 77 via the outlet port 62, the annular groove 37, the fluid passage 36, the horizontal fluid exhaust passage 15, the vertical fluid passage 14, the horizontal fluid passage 13 and the fluid exhaust pipe 25. Shocks caused by the above-described reciprocal movement of the reciprocator 60 in the main bore 31 are effectively absorbed by the cushion abutments 43 and 44 provided on both ends of the main bore 31 interior.

In connection with the above-described discharging system of the pressured fluid out of both side fluid chambers 77 and 78, it should be greatly appreciated that, in the upstream part of the fluid discharging line, pressured fluids from the different chambers flow along different courses and the different courses join with each other at a location appreciably remote from the positions of the chambers. Thanks to this specially designed arrangement of the fluid discharging system, the discharge of the pressured fluid can be carried out very smoothly without being influenced by the pressured condition inside the chambers. More specifically, in the embodiment shown in FIG. 1, the pressured fluid from the left side chamber 77 flows through the upper exhaust passage 15, whereas the pressured fluid from the right side chamber 78 flows through the lower exhaust passage 34 which runs almost parallel to, but clearly separated from, the upper exhaust passage 15. However, in the vicinity of the rear end of the interior of the main hand grip 10, both passages 15 and 34 merge into a common passage, i.e. the 2nd fluid passage 14.

The reciprocal movement of the reciprocator 60 so caused accompanies corresponding and concurrent reciprocal movement of the filing part 90 via the carrier legs 73 and 74 of the sealing caps 71 and 72. This reciprocal movement of the filing part 90 is carried out very smoothly due to the insertion of the roller bearing assembly 100 between the bottom face of the main body 30 and the top side of the filing part 90. By the above-mentioned reciprocal movement of the filing part 90, the body file 95 carries out the filing work through its sliding contact with the surface to be finished.

So that the reciprocator 60 does not exert too much downward pressure against the wall of the main bore 31 and undesirably damage the same when the machine is

driven in an unloaded condition, the pressured fluid is introduced into the cut-out (reservoir) 66 from the annular grooves 83 and/or 84 via the passage 67. By this introduction of the pressured fluid into the underside 5 cut-out 66, the reciprocator 60 is maintained in a somewhat lifted condition during its reciprocation and damage to the main bore wall can be effectively prevented.

As already described, the sealing caps 71 and 72 are 10 fixed to the ends of the reciprocator 60 by pins 69 and 70. In a preferred embodiment of the filing machine of the present invention, the length of at least one of the pins 69 and 70 is selected shorter than the inner diameter of the cylindrical reciprocator 60. By designing the 15 pins in this way, the sealing caps 71 and 72, together with the filing part 90, can be very easily disassembled from the body of the machine by simply punching the pins 69 and/or 70 into the holes.

What is claimed is:

1. A reciprocating type portable filing machine comprising, in combination, a main hand grip adapted for an operator's handling of the machine and provided with a fluid intake passage and a first fluid exhaust passage; a pressured fluid supply system external of said main hand grip and connecting said fluid intake passage to a given supply source of said pressured fluid; a used fluid exhaust system external of said main hand grip and connected to said first fluid exhaust passage; a finger operable valve and its related assembly incorporated within said main hand grip for control of the pressured fluid supply through said fluid intake passage; a hollow main body disposed to the bottom of said main hand grip confining a longitudinally elongated main bore which is closed at both ends and provided with a fluid intake hole connected to said fluid intake passage of said main hand grip and a second fluid exhaust passage joining at its downstream end with said first fluid exhaust passage; a fluid actuated cylindrical reciprocator encased within said main bore in an axially reciprocating arrangement and provided with fluid inlet ports capable of being connected to said fluid intake hole of said main body and also provided with fluid outlet ports connected to said first fluid exhaust passage and said second fluid exhaust passage, respectively; means arranged on both inner closed ends of said main bore and for resiliently resisting the reciprocation of said reciprocator; a piston encased within said reciprocator in an axially reciprocating arrangement and provided with fluid intake passages communicable to said fluid inlet ports of said reciprocator; a filing part disposed downwards of said reciprocator in an arrangement coactive with the latter; and a roller bearing assembly inserted between the bottom outer face of said main body and the upper face of said filing part.

2. A reciprocating type portable filing machine as claimed in claim 1 wherein said main hand grip is internally provided with a front bore which opens on the front side of said hand grip and at its rear end communicates with said fluid intake passage and said valve and its related assembly includes a finger operable trigger pivoted at the front opening of said front bore, a valve actuator pivoted to said trigger and extending rearwardly through said front bore and a valve member disposed at the junction of said front bore with said fluid intake passage in an arrangement capable of being activated by said valve actuator.

3. A reciprocating type portable filing machine as claimed in claim 1 wherein cushion abutments are provided on both closed ends of said main bore.

4. A reciprocating type portable filing machine as claimed in claim 1 wherein said fluid exhaust passage joins with said first fluid exhaust passage at a point remote from their upstream ends.

5. A reciprocating type portable filing machine as claimed in claim 1 wherein the internal chamber of said reciprocator is closed at both ends by sealing caps detachably fixed to the cylindrical wall thereof.

6. A reciprocating type portable filing machine as claimed in claim 5 wherein the fixing of said sealing cap to said cylindrical wall is effected by a pin at least one of whose length is shorter than the internal diameter of the chamber.

7. A reciprocating type portable filing machine as claimed in claim 5 wherein said sealing caps are provided with downwardly extending carrier legs for carrying said filing part.

8. A reciprocating type filing machine as claimed in claim 1 wherein said fluid inlet ports of said reciprocator reduce their transverse cross sectional areas as they deviate from the middle of the length of said reciprocator.

9. A reciprocating type portable filing machine as claimed in claim 1 wherein said resilient resisting

means is given in the form of coil compression springs placed between outer end faces of said reciprocator and corresponding inner closed ends of said main bore.

10. A reciprocating type portable filing machine as claimed in claim 1 wherein one of said fluid intake passages of said piston opens at the front end face of said piston and the other of said fluid intake passages opens at the rear end face of said piston.

11. A reciprocating type portable filing machine as claimed in claim 1 wherein said filing part includes a support layer, a cushion layer disposed underneath of said support layer an intermediate friction layer disposed underneath said cushion layer and a body file detachably arranged underneath said intermediate friction layer.

12. A reciprocating type portable filing machine as claimed in claim 1 wherein said roller bearing assembly includes a carrier plate, a plurality of bearing rollers which are axially rotatably carried by said carrier plate in a spaced side by side arrangement with their axes running at right angles to the direction of reciprocation of said filing part, a supporter plate disposed underneath said bearing rollers and a guide frame fixed on said filing part and accommodating the above recited elements in its center cavity.
